Primary Examiner — Cathron C Brooks*Assistant Examiner* — W. A. Teddy Falloway(74) Attorney, Agent, or Firm — Seager, Tufte & Wickhem LLP(57) CLAIM

The ornamental design for a dual cosmetics jar, as shown and described.

DESCRIPTION

FIG. 1 is a perspective view of a dual cosmetics jar showing the new design;

FIG. 2 is a front elevational view thereof, the rear, left, and right views being the same as the front view thereof;

FIG. 3 is a top view thereof, the bottom view being a mirror image thereof;

FIG. 4 is a front elevational view thereof, with the two jars separated from the central lid assembly, the two jars being identical; and,

FIG. 5 is a perspective exploded view thereof.

The broken lines illustrate portions of the dual cosmetics jar that form no part of the claimed design.
